(57) **CLAIM**

The ornamental design for the railroad spike golfer figurine, as shown and described.

DESCRIPTION

Using six asymmetric railroad spikes, the spikes are welded together to simulate a golfer. They are used for ornamental purposes, i.e.; home and office decor, trophy, yard art, book ends and the like. The figurine is unique in that it recycles historical railroad spikes into modern art.

FIG. 1 is the front view of a railroad spike golfer figurine showing my new design;

FIG. 2 is a rear view thereof;

FIG. 3 is a left side view thereof;

FIG. 4 is a right side view thereof;
